[57] **CLAIM**

The ornamental design for a combination knife and utility tool with pivotal blade cover, as shown and described in the drawings.

DESCRIPTION

FIG. 1 is a perspective view looking at the top and one side of the combination knife and utility tool with pivotal blade cover, showing the blade cover seated in a first operative position exposing the blade of the knife; FIG. 2 is a side elevation of the combination knife and utility tool with pivotal blade cover illustrating movement of the pivotal hand grip between the first operative position of FIG. 1 and a second operative position of FIG. 3; and

FIG. 3 is a perspective view of the combination knife and utility tool with pivotal blade cover looking at the top and side opposite that shown in FIG. 1 and illustrating the pivotal blade cover seated in its second operative position about the sharpened edge of the knife blade.
